United States Patent Office

Des. 210,764
Patented Apr. 16, 1968

210,764

BED HEADBOARD, OR SIMILAR ARTICLE

Calvin K. Kessler, El Paso, Tex., assignor to Kessler Industries, Inc., El Paso, Tex., a corporation of Texas

Filed Mar. 21, 1967, Ser. No. 6,316

Term of patent 14 years

(Cl. D5—4)

FIG. 1 is a front elevational view of a bed headboard showing my new design;

FIG. 2 is a rear elevation thereof; and

FIG. 3 is a plan view thereof looking down on the bed headboard in vertical position.

I claim:

The ornamental design for a bed headboard, or similar article, substantially as shown.
